UNITED STATES PATENT OFFICE.

ROY L. KENYON, OF WAUKESHA, WISCONSIN.

KNOCKDOWN FRAME FOR PORTABLE BUILDINGS.

1,083,404.

Specification of Letters Patent.

Patented Jan. 6, 1914.

Application filed March 10, 1910. Serial No. 548,392.

To all whom it may concern:

Be it known that I, ROY L. KENYON, a citizen of the United States, residing at Waukesha, in the county of Waukesha and 5 State of Wisconsin, have invented certain new and useful Improvements in Knockdown Frames for Portable Buildings, of which the following is a specification, reference being had to the accompanying drawing, forming a part thereof.

This invention relates more particularly to the joints connecting the various members of the frame for a portable cottage or building.

15 Its main objects are to facilitate putting up and taking down the frames of portable buildings without tools; to avoid cutting away and consequently weakening the members of the frame and generally to simplify, 20 improve and increase the convenience of such structures.

It consists in the construction, arrangement, and combination of parts as herein-after particularly described and defined in 25 the claims.

In the accompanying drawing like characters designate the same parts in the several figures.

Figure 1 is a perspective view showing an 30 assembled knockdown frame embodying the invention; and Figs. 2 to 8 inclusive are detail perspective views on an enlarged scale showing the joints and fastenings for assembling and securing together various members of the frame.

For the purpose of illustration and explanation of the invention, a frame as constructed for a portable cottage or building of comparatively large size is shown, but 40 the number and arrangement of the component members of the frame may be varied for buildings of different sizes and for various purposes, without change in the essential features of construction and without 45 departure from the principle of the invention.

Referring to Fig. 1 of the drawing, the frame comprises side floor sills or base rails *a*, side top rails or beams *b*, corner posts *c*, 50 intermediate side posts *c'*, end center posts *d*, an intermediate center post *d'*, end floor sills or base rails *e*, a ridge pole *f* adapted to rest on the tops of the center posts *d* *d'*, rafters *g* extending from the ridge pole to the corner and side posts *c* *c'*, and tie rails or beams *h* connecting the center posts *d* *d'* with the

rafters on each side. At either or each end the frame may have, as shown, a door post *i* extending from one of the tie rails or beams *h* downwardly to the opposite floor sill or base rail *e*, and connected by a door sill *e'* with the adjacent center post *d*, thereby forming a door frame. The frame may be stayed lengthwise by diagonal braces *j* fastened at one end to the center posts *d* and 60 extending upwardly therefrom to the ridge pole *f*, to which they are fastened at the other end.

For small buildings the intermediate side posts *c'* and center post *d'* may be dispensed with and the corner posts on each side of the building connected directly with each other by single base and top rails *a* and *b*, and for larger buildings the frame may be extended by adding any desired number of 75 sections with intermediate side and center posts *c'* and *d'*, as shown.

The center posts *d*, ridge pole *f* and rafters *g* are detachably fastened together and held in the proper relation to one another 80 when the frame is assembled, as shown by Fig. 2. For this purpose each center post is provided at the upper end with a central vertical tenon 2, which may consist of a metal pin driven or screwed into the post. 85 It is also provided adjacent to its upper end with two transverse metal plates or bands 3, which are riveted or otherwise fastened parallel with each other to opposite faces of the post, and are connected adjacent to their ends which project beyond the remaining sides of the post by cross pins 4, forming with the plates, loops, eyes, or keepers for engagement with hooks 5 on the rafters *g*. These hooks may be made as shown, of 90 strips of band iron or steel bent to the desired shape and riveted or otherwise fastened to the under side of the rafters, adjacent to their ends which are chamfered or beveled to fit against the opposite sides of 100 the ridge pole *f*. The ridge pole is formed with a vertical mortise, socket or hole 6, as indicated by dotted lines, to fit upon the tenon or pin 2. The upper end of the center post is formed with a square face on 105 which the ridge pole rests around the tenon or pin 2, and on opposite sides of this square face with beveled faces on which the upper ends of the rafters *g* rest.

The parts are assembled and secured together by placing the ridge pole *f* on the tenon or pin 2, engaging the hooks 5 with

the cross pins 4, and then raising the outer ends of the rafters into place and fastening them to the top rails *b* and corner posts *c*, as hereinafter explained. When so assembled,

5 the inner and upper chamfered or beveled ends of the rafters bear against opposite sides of the ridge pole and thus help to hold it securely in place. The outer and lower ends of the rafters are fitted to and rest upon the upper ends of the corner posts *c* and are fastened thereto and to the top rails *b*, as shown in detail by Fig. 4.

10 Each corner post is provided at its upper end with a pin or tenon 7 which fits into a corresponding socket, mortise or hole 8 in the associated rafter *g*, thereby securely holding these members of the frame in the proper relation to each other. The post *c* is also provided adjacent to its upper end with a loop 9, which may be formed in a strip of band iron or steel riveted or otherwise fastened to the post. The adjacent end of the associated top rail *b* is provided on the under side with a downwardly projecting hook 10 which fits into the loop 9 on the corner post and which may consist of a strip of band iron or steel bent to the desired shape and riveted or otherwise fastened to said rail. This rail is also provided 20 on the under side with an angular metal plate 11 which has an inwardly projecting and vertically notched limb adapted to engage with the inner end of a bolt 12 passing transversely through the associated rafter *g* when the parts are assembled, as 25 shown in Fig. 1. The bolt 12 as well as all of the bolts employed in the frame, is preferably provided with a winged thumb nut 13 to avoid the necessity of using a wrench 30 in assembling the members of the frame and taking them apart.

35 The tie rails or beams *h* are connected at their inner ends with the associated center post *d* by fastenings as shown in detail by 40 Fig. 3. To the center post at the required point a metal band 14 is fastened by rivets or other means, and on opposite sides of the post this band is formed into loops to receive and hold hooks 15 attached to the under side of the rails or beams *h* at their inner ends. These hooks may be formed of band 45 iron or steel bent to the desired shape and riveted or otherwise fastened to said rails or beams. On their upper sides the rails or beams *h* are provided with longitudinally notched or forked angle plates 16, which are 50 adapted to be engaged with the ends of a bolt 12 passing transversely through and movable up and down in a longitudinal slot 55 17 formed in the center post *d*. When the hooks 15 have been inserted in the loops of the plate or band 14, the bolt 12 is moved downward in the slot 17 into engagement with the notches or upwardly projecting 60 65 forked limbs of the angle plates 16. The

nut 13 is then tightened on the bolt and the parts are thus securely fastened together in the proper relation to one another.

The outer ends of the tie rails or beams *h* are secured to the rafters *g* as shown in detail by Fig. 5. The ends of the rails or beams *h* which are beveled to fit against the rafters on the under side thereof, are provided with longitudinally notched or forked angle plates 18 fastened to the under side of said rails or beams with their forked or notched limbs substantially flush with said beveled ends, and adapted to be engaged with the protruding lower ends of bolts 12 passing transversely through the rafters *g* at the proper points therein. Like or similar fastenings may be used to secure the braces *j* to the center posts *d* and ridge pole *f*.

70 Where a member of the frame abuts at one end against a side of another member between the ends thereof, as at the upper end of the door post *i* where a tie rail *h* rests upon it, they may be connected by fastenings as shown in detail by Fig. 6. The vertical member *i* is provided at its upper end on opposite sides with longitudinally notched or forked angle plates 16 adapted to be engaged with the protruding lower ends of bolts 12 passing transversely through the horizontal member *h*, one of 75 said bolts being movable, when its nut 13 is loosened, toward and from the other in a longitudinal slot 17 formed in said member *h*, to permit the assemblage and separation of the members.

80 Where two members of the frame are joined to adjacent sides of a third member at the end thereof, as where floor sills or base rails *a* and *e* are joined to the lower end of a corner post *c*, they may be connected by 85 fastenings as shown in detail by Fig. 7. The rail *a* is provided on the inner side at each end with a transversely notched angle plate 11 and the rail *e* is provided on the outer side at the adjacent end with a transversely notched straight plate 19, the plate 90 95 11 being adapted for engagement with the inner end and the plate 19 for engagement with the outer end of a bolt 12 passing transversely through the post *c* parallel with the rail *a*.

100 Where one member of the frame is joined to a side of another member at the end thereof, as where the sills or rails *e* and *e'* are joined to the lower ends of the center posts *d* and door post *i*, they may be connected by a double fastening, as shown in detail in Fig. 8, consisting of two transversely notched plates 19, riveted or otherwise fastened to opposite sides of the rail *e* 105 lengthwise thereof, and a bolt 12 passing transversely through the post *i* in position to be engaged at its protruding ends with the notches in said plates.

110 Where two rails or members such as the 115

end floor sills *e* and the door sill *e'* are joined to opposite sides of a third member such as a center post *d* or door post *i* at the end thereof, two pairs of notched plates 19 5 may be engaged with a single bolt 12 in the intermediate member by bending the plates of one pair outwardly so as to overlap the plates of the other pair, as shown in Fig. 1.

In frames for larger buildings, where intermediate side posts *c'* are employed, and are each connected at their upper ends with a rafter and two top rails or beams *b*, the metal band adjacent to the upper end of each post is formed with loops 9 on opposite sides, as shown in Fig. 1, to receive the hooks 10 of the adjoining rails *b*.

By means of the joints and fastenings constructed and arranged as shown and hereinbefore described, the various members of the frame may be easily and quickly assembled 20 and taken apart without tools, and when so assembled and connected will form a stable structure.

Some of the fastenings may be used in different locations in the frame or substituted one for another, and in details of construction and arrangement of parts the fastenings as well as the members of the frame, may be modified in various ways in the 25 adaptation of the invention to buildings of different sizes for various purposes, as will be apparent to those familiar with the art to which the invention pertains.

When a floor is provided, it is laid upon 35 and supported by the sills or base rails *a* and *e*.

The frame itself may be leveled and supported in any convenient manner, for instance, by stakes *k* driven into the ground 40 in position for the posts *c*, *c'*, *d*' and *i* to rest upon, as shown in Fig. 1.

I claim:

1. In a knockdown frame for portable buildings the combination of a center post, 45 a ridge pole adapted to rest upon the upper end of said post, rafters having beveled ends fitted against the opposite sides of the ridge pole, and fastenings for detachably securing said parts together with the ridge pole confined between the beveled ends of the rafters said fastenings consisting of members on opposite sides of the center post adjacent to its upper end and of members on the under sides of the rafters adjacent to their inner ends adapted to be engaged with the members on the center post when the outer ends of the rafters are lowered and to be interlocked therewith when the outer ends of the rafters are elevated into place.

60 2. In a knockdown frame for portable buildings the combination of a center post having oppositely beveled faces at the upper end, a ridge pole adapted to rest upon the upper end of said post between said 65 beveled faces, rafters having beveled ends

fitted to opposite sides of the ridge pole and adapted to rest adjacent thereto upon the beveled end faces of the center post, and fastenings for detachably securing said parts together with the ridge pole confined between the beveled ends of the rafters said fastenings consisting of members on opposite sides of the center post adjacent to its upper end and of members on the lower sides of the rafters adjacent to their inner ends 70 adapted to be engaged with the members on the center post when the outer ends of the rafters are lowered and to be interlocked therewith when the outer ends of the rafters are elevated into place.

3. In a knockdown frame for portable buildings the combination of a center post and a ridge pole adapted to rest upon the upper end of said post, one of said parts having a tenon fitting into a socket in the other part, rafters fitted to abut at one end against opposite sides of the ridge pole and fastenings adapted to detachably secure the rafters to the center post with the ridge pole confined between the inner ends of the rafters said fastenings consisting of keepers on opposite sides of the center post adjacent to its upper end and of hooks on the lower sides of the rafters adjacent to their inner ends 85 adapted to be engaged with said keepers when the outer ends of the rafters are lowered and to be interlocked therewith when the outer ends of the rafters are elevated into place.

4. In a knockdown frame for portable buildings the combination of a center post provided at the upper end with a tenon and adjacent thereto with cross plates connected on opposite sides of the post by pins, a ridge pole having a socket removably fitted on 105 said tenon, and rafters provided on their lower sides adjacent to their inner ends with hooks adapted to engage with said pins when the outer ends of the rafters are lowered and to detachably secure the rafters to the center post when the outer ends of the rafters are elevated into place, and confining the ridge pole between their inner ends.

5. In a knockdown frame for portable buildings the combination of a vertical member formed with a longitudinal slot and provided adjacent thereto with a metal band formed into loops on opposite sides thereof, a bolt passing loosely through said slot, and horizontal members each provided at one 115 end on opposite sides with angular metal plates or hooks, one of the plates or hooks of each horizontal member fitting into a loop of the band on the vertical member while the other is forked for engagement with one 120 end of said bolt.

6. In a knockdown frame for portable buildings, the combination of a vertical member having a vertical pin or tenon at its upper end and a loop on one side adja- 125

cent thereto, an inclined member fitted at one end to the upper end of the vertical member and provided with a socket to receive said pin or tenon and with a bolt passing horizontally through it, and a horizontal member provided at one end on adjacent sides with angular plates or hooks one of which fits into said loop of the vertical member

while the other is laterally notched to engage with the bolt in the inclined member.

In witness whereof I hereto affix my signature in presence of two witnesses.

ROY L. KENYON.
